SIDING PANEL

Samuel Borger and William Borger, New York, N. Y.,
assignors to Bird & Son, Inc., East Walpole, Mass., a
corporation of Massachusetts

Application September 21, 1956, Serial No. 43,029

Term of patent 14 years

(Cl. D13—1)

Fig. 1 is a front elevational view of a siding panel showing our new design; and

Fig. 2 is an enlarged cross-sectional view taken along 2—2 of Fig. 1.

We claim:

The ornamental design for a siding panel, substantially as shown.
